FIG. 7.

A geological cross-section diagram. At the top, a wavy line represents the surface. Below it, a series of vertical columns are arranged. The first column is labeled 'p'. The second column is labeled 'l'. The third column is labeled 'p'. The fourth column is labeled 'r'. Below these four columns is a horizontal line with a label 'd''. To the left of the diagram, the label 'XII' is written vertically. To the right, the label 'hgt' is written vertically, with 'h' at the top, 'g' in the middle, and 't' at the bottom, with a small 's' at the very bottom.

Inventor *Daniel Richards*
By *Henry Orth* Atty.

UNITED STATES PATENT OFFICE.

DANIEL RICHARDS, OF WINCHMORE HILL, ENGLAND, ASSIGNOR OF ONE-HALF TO
DYSON & COMPANY, (ENFIELD) LIMITED, OF PONDERS END, ENGLAND.

TOOL-HOLDER.

1,295,600.

Specification of Letters Patent.

Patented Feb. 25, 1919.

Application filed September 1, 1917. Serial No. 189,327.

To all whom it may concern:

Be it known that I, DANIEL RICHARDS, a subject of the King of Great Britain and Ireland, residing at No. 99 Woodberry avenue, 5 Winchmore Hill, in the county of Middlesex, England, have invented certain new and useful Improvements in and Connected with Tool-Holders, of which the following is a specification.

10 This invention relates to improvements in and connected with tool-holders for lathes, planing machines and other machine tools, of the type in which the end of the shank is provided with a cutter-holding part, furnished with jaws and adapted to receive and retain the cutter, a locking roller or rollers mounted in a recess or recesses having an inclined surface or surfaces and guided at each end in a groove in the cutter-holding part 15 20 and a spring for each roller, mounted in such a manner as to tend to force the roller toward the narrow end of each recess, for the purpose of causing such a roller to roll and lock the cutter in position. The object of 25 30 the invention is to improve a tool-holder of this kind, to prevent parts thereof from becoming displaced and lost and to insure that the cutter shall always be locked in position, irrespective of the direction of travel of the tool or the work.

The invention comprises also various minor improvements which will appear in the following description and are defined in the claims, reference being had to the accompanying drawings, in which

Figure 1 of the accompanying drawings is a front elevation of a tool holder with a straight shank and a cutter applied thereto;

Fig. 2 is a part sectional side elevation;

40 Fig. 3 is a plan section on the line III—III, Fig. 2.

Fig. 4 is an elevation of a locking roller to a larger scale;

Fig. 5 is an elevation of a spring for pressing on a locking roller, and

Fig. 6 is a plan thereof.

Fig. 7 is an elevation of a modified construction of spring, and

Fig. 8 is a plan thereof.

50 Fig. 9 is a front elevation of a modified construction of tool holder.

Fig. 10 is a section thereof on the line X—X Fig. 9, but without the rollers springs and cutter.

Fig. 11 is a similar view, including also 55 rollers springs and cutter and

Fig. 12 is a plan section on the line XII—XII, Fig. 11.

In carrying the invention into effect and according to the construction shown in Figs. 60 1 to 6 inclusive, the shank *a* has at one end thereof, a cutter-holding part *b*, recessed to form jaws *c* adapted to receive and retain the tool or cutter *d*, which is of a cross section to correspond to the jaws of the cutter-holding part, and is furnished with a neck *e* and two lateral projections *f*. At the rear of this recess, there is a block or abutment *g*, suitably held in place by having a projection *h* adapted to take into a recess between the 70 jaws of the cutter-holding part and locked in position by two screws *i*. Or the abutment may be integral with the cutter holding part *b*. A transverse and tangential or inclined recess or recesses *k*, or preferably 75 three of such recesses is or are made in the block and within each of these recesses is mounted a roller *l*. Each jaw *c* of the cutter-holding part is, moreover, provided with a groove *m*, the ends of the rollers are reduced and these reduced ends *l'* of the rollers are adapted to be guided in these grooves. Each roller is pressed toward the shallower end of its recess by means of a bent spring *n* (Figs. 5 and 6) recessed or made like a fork 80

o at each end so as, in each case, to partially embrace the roller near its ends. Preferably, however, and as shown in Figs. 7 and 8, double bow-shaped springs *p* are employed. The two upper and longer ends *q* of the 90 spring blank, Fig. 8, are shaped to fit within the grooves *m* in the cutter-holding part and to abut against the wall or surface at the deep end of the recess, while the two shorter ends are shaped to form forks *o'* so as to 95 partially embrace the roller *l*. The two portions *p'* and *p''* of the blank are connected at *p''* and when folded on each other bent and tempered, they are made to assume the form shown by Fig. 7. When the rollers and 100 spring are in position as shown in the construction shown in Figs. 2 and 3, the rollers tend to be parallel to the deep ends *l'* of the recess *k* irrespective of their position therein and whether they are in engagement with the cutter *d* or whether the latter has been removed from the holder.

In the construction shown in Figs. 9 to 12,

the block or abutment *g* is, moreover, furnished with another inclined recess *s*, the rear surface of which has an angularity opposite to that of those just described, a 5 double bow spring *p* and a locking roller *r*. In order to put this roller out of action when inserting or removing a cutter, the block is conveniently provided with a hole *t* at the top communicating with the inclined recess 10 *s*, for the insertion of a pin, screw or the like for displacing the roller *r*, when it is desired to remove the cutter *d'* from the jaws *c* of the tool holder and it is then only necessary to knock or force the cutter *d'* upward 15 whereupon the rollers *l* come away from intimate engagement with the rear faces of the recesses and the rear surface of the cutter.

According to another construction the cutter-holding part is hinged to the shank 20 and both the shank and the cutter-holding part are provided with stops, so that when the tool is cutting, one stop on the cutter-holding part is in contact with the corresponding stop on the shank. But if, as in 25 a planing machine, the work is being moved past the cutter on the return stroke, the tool-holding part being hinged and there being a certain amount of play between the other two stops, the cutting edge of the 30 cutter is less deleteriously affected than if, for example, it had the whole resistance due to the weight of the tool box to overcome. In order, however, that the cutter shall always tend to resume its proper position 35 for cutting, a small spring is interposed and a suitable form of spring is a helical spring mounted in a shallow hole in each of the stops for determining the amount of movement to be allowed between 40 the tool-holding part and the shank during the return stroke.

Finally, in order to allow of utilizing the tool-holder as a front or a side tool, the cutter in some cases being the same, the 45 tool holding part is hinged to the shank and the pivot is provided with a nut and a lock nut or the like, if desired. For the purpose, however, of preventing slipping between the two parts, each is wholly or 50 partially provided with a circular rack on the surfaces to be engaged when the parts are clamped together. The nut then only requires to be slackened and the tool-holding part is then partially rotated and 55 screwed up in the position required.

What I claim is:—

1. A tool holder, for lathes, planing machines and other machine-tools, comprising in combination, a shank, a cutter holding 60 part at one end of the said shank, and having jaws to receive and retain a correspondingly formed cutter between them, a recess to the rear of and between the said 65 jaws and having its rear surface angular to the plane in which the rear surface of

the cutter is situated, a groove at each side of the cutter holding part, a locking roller having its ends fashioned to loosely engage in the said grooves, a bent spring, and means on the latter whereby it partially embraces the roller in the vicinity of its ends. 70

2. A tool holder, for lathes, planing machines and other machine-tools, comprising in combination a shank, a correspondingly formed cutter holding part at one end of the said shank and having jaws to receive and retain a cutter between them, a plurality of recesses to the rear of and between the jaws and having their rear surfaces angular to the plane in which the 80 rear surface of the cutter is situated, a groove, at each side of the said recesses, a locking roller for each recess, the ends of said locking roller being adapted to loosely engage in the said grooves, and a bent spring mounted in each recess so that its ends constantly press on the roller near its ends, the ends of the said spring being fork shaped so as to partially embrace the 85 roller. 90

3. A tool holder, for lathes, planing machines and other machine-tools, comprising, in combination a shank, a cutter holding part, at one end of the said shank and having jaws to receive and retain a correspondingly formed cutter between them, a plurality of recesses to the rear of and between the said jaws, the said recesses having their rear surfaces angular to the plane in which the rear surface of the cutter is 95 situated, a groove at each side of the said recesses, a locking roller in each recess, the ends of said rollers adapted to loosely engage in the said grooves, and a double bow-spring mounted in each recess, two of the 100 ends of the said spring being fork-shaped so as to partially embrace the roller in the said recess. 105

4. A tool holder, for lathes, planing machines and other machine-tools, comprising, in combination, a shank, a cutter holding part, at one end of the said shank and having jaws to receive and retain a correspondingly formed cutter between them, a plurality of recesses to the rear of and between the said jaws, the said recesses having their rear surfaces angular to the plane in which the rear surface of the cutter is situated, a groove at each side of the said recesses, a locking roller in each recess, the 110 ends of said rollers adapted to loosely engage in the said grooves, and a double bow-spring mounted in each recess, the ends of one bow portion of the said spring being fork-shaped so as to partially embrace the 115 roller in the said recess and the ends of the other bow portion adapted to loosely engage in the said grooves. 120

5. A tool holder, for lathes, planing machines and other machine tools, comprising, 125

in combination, a shank, a cutter holding part at one end of the said shank and having jaws to receive and retain a cutter between them, a plurality of recesses to the rear of them, and between the said jaws, the said recesses having their rear surfaces angular to the plane in which the rear surface of the cutter is situated, a groove at each side of the said recesses, a locking roller for each recess, the ends of said locking rollers adapted to engage in the said grooves, a double bow-spring mounted in each recess, the ends of one bow-portion of the said spring being fork-shaped so as to partially embrace the roller in the said recess, the ends of the other bow portion adapted to loosely engage in the said grooves, another recess having its rear surface angular to the plane in which the rear surface of the cutter is situated and of an inclination opposite to that of the aforesaid recesses, a locking roller in the said recess, the ends of said locking roller adapted to engage in the aforesaid grooves, a bent spring, fork shaped at its ends and partially embracing the said roller near its ends and means for displacing the roller to admit of the renewal of the cutter.

6. A tool holder for lathes, planing machines and other machine tools, comprising, in combination, a shank, a cutter holding part at one end of the said shank and having laterally recessed jaws to receive and retain a cutter having an engaging part of corresponding cross-section, an abutment block adapted to be fixed between the said jaws, means for fixing the said abutment block, a plurality of recesses in the said block the rear surfaces of the said recesses being angular to the front surface of the said block, a groove in each jaw, a locking roller for each recess, the ends of said locking roller being adapted to loosely engage in the said grooves and a bent spring mounted in each recess, so that its ends constantly press on the roller near its ends, the ends of the said spring being fork-shaped so as to partially embrace the roller.

7. A tool holder, for lathes, planing machines and other machine tools, comprising, in combination, a shank, a cutter holding part at one end of the said shank and having laterally recessed jaws to receive and retain a cutter having an engaging part of corresponding cross section, an abutment block adapted to be fixed between the said jaws, means for fixing the said abutment block, a plurality of recesses in the said block, the rear surfaces of the said recesses being angular to the front surface of the said block, a groove in each jaw, a locking roller in each recess, the ends of said rollers adapted to loosely engage in the said grooves and a double bow-spring mounted in each recess, two of the ends of the said spring being

fork-shaped so as to partially engage the 65 roller in the said recess.

8. A tool holder, for lathes, planing machines and other machine tools, comprising in combination, a shank, a cutter holding part at one end of the said shank and having laterally recessed jaws to receive and retain a cutter having an engaging part of corresponding cross section, an abutment block adapted to be fixed between the said jaws, means for fixing the said abutment 70 block, a plurality of recesses in the said block, the rear surfaces of the said recesses being angular to the front surface of the block, a groove in each jaw, a locking roller in each recess, the ends of said rollers 75 adapted to loosely engage in the said grooves and a double bow-spring mounted in each recess the ends of one bow-portion of the said spring being fork-shaped, so as to partially embrace the roller in the said recess 80 and the ends of the other bow-portion, adapted to loosely engage in the said grooves.

9. A tool holder for lathes, planing machines and other machine tools, comprising, 90 in combination, a shank, a cutter-holding part at one end of the said shank and having laterally recessed jaws to receive and retain a cutter having an engaging part of corresponding cross section, an abut- 95 ment block adapted to be fixed between the said jaws, means for fixing the said abutment block, a plurality of recesses in the said block, the rear surfaces of the said recesses being angular to the front surface of 100 the block, another recess having its rear surface angular to the front surface of the block but of an angularity opposite to that of the aforesaid recesses, a groove in each jaw, a locking roller in each recess, the 105 ends of said rollers adapted to loosely engage in the said grooves, a double bow spring mounted in each recess the ends of one bow-portion of each of the said springs being fork-shaped, so as to partially embrace the roller in the said recess, and the ends of the other bow-portion adapted to loosely engage in the said grooves and means for displacing that roller which is mounted in the recess having its rear surface of opposite angularity to that of the aforesaid plurality of recesses.

10. A tool holder, for lathes, planing machines and other machine tools, comprising in combination a shank, a cutter-holding part at one end of the said shank and having laterally recessed jaws to receive and retain a cutter having an engaging part of corresponding cross section, a recess 120 at the top, to the rear of and between the said jaws, an abutment block adapted to fit between the said jaws and having a projection to engage in the said recess, means

for rigidly retaining the said abutment block in place, a plurality of transverse recesses in the said block, the rear surfaces of the said recesses being angular to the front surface of the block the upper recess having its rear surface of an angularity opposite to that of the other recesses, a vertical groove in each jaw intersecting the said recess, a locking roller in each recess, the ends of said rollers adapted to loosely engage in the said grooves, a double bow spring mounted in each recess, the ends of one bow-portion of each of the said springs being fork-shaped, so as to partially embrace the roller in the said recess, and the ends of the other bow-portion adapted to loosely engage in the said grooves and a hole through the top of the block into the uppermost recess for the insertion of an instrument to displace the said upper roller.

11. In a tool holder, for lathes, planing

machine and other machine tools the combination with a shank, a cutter holding part at one end of the said shank and having jaws to receive and retain a cutter having 25 an engaging part of a cross section corresponding to that of the said jaws, a plurality of transverse recesses at the rear of the said jaws, the rear surfaces of the said recesses being angular to the rear surface 30 of the cutter, a roller in each of said recesses and the ends of the said rollers adapted to freely engage in the said grooves, of a double bow-spring in each of the said recesses the bow portion being back to back 35 and joined at one side, the two ends of one bow portion conforming to and loosely fitting in the said grooves and the two ends of the other bow portion adapted to partially embrace the roller.

DANIEL RICHARDS.
